UNITED STATES PATENT OFFICE.

WILLIAM FEDER, OF CHICAGO, ILLINOIS, ASSIGNOR TO THEO. B. ROBERTSON
PRODUCTS CO., OF CHICAGO, ILLINOIS, A CORPORATION OF ILLINOIS.

BRUSH.

1,385,532.

Specification of Letters Patent. Patented July 26, 1921.

Application filed August 16, 1919. Serial No. 317,864.

To all whom it may concern:

Be it known that I, WILLIAM FEDER, a citizen of the United States, and a resident of the city of Chicago, in the county of Cook and State of Illinois, have invented certain new and useful Improvements in Brushes; and I do hereby declare that the following is a full, clear, and exact description of the same, reference being had to the accompanying drawings, and to the numerals of reference marked thereon, which form a part of this specification.

This invention relates to brushes and processes for manufacturing the same and also though not restricted to such use is particularly adapted for brushes in household use.

I have found that in many brushes the bristles are frequently not firmly secured to the head for the reason that no wedging action is employed for holding them in place.

One of the principal objects, therefore, of the present invention is to provide a brush having a continuous row of bristles extending substantially the entire length of the brush.

A further object of the invention is to provide wedging means for securing the bristles in place.

A further object of the invention is to provide an improved form of cement which is both insoluble in water and also unaffected by moderate heat.

Other and further important objects of the invention will be apparent from the disclosure in the following specification and the accompanying drawings.

The invention in a preferred form is illustrated in the drawings and hereinafter more fully described.

On the drawings:

Figure 1 is a side elevation of a broom embodying the features of the present invention.

Fig. 2 is a plan view of the head of the broom.

Fig. 3 is a front elevation of the head of the broom.

Fig. 4 is a section on the line 4-4 of Fig. 2.

Fig. 5 is a plan view of the bristles support with the top of the broom head removed therefrom.

As shown on the drawings:

The broom comprises a head 1, having a pair of diagonally arranged holes 2, for al-

ternate engagement with a broom stick 3, in well known manner. The head 1, includes a bristle support 4, and a top piece 5, secured thereto by suitable means such as screws 6, or glue or other adhesive. 60

In the support 4, slots 7, are formed. Conveniently these slots may be made by drilling holes in the end of the support and then cutting out the intervening material by means of a band saw. When these slots 65 have been formed, a row of bristles 8, are inserted evenly in each of the slots and then down the center of each row a wedge strip 9, is forced so as to firmly press the bristles against each wall of the slots. These wedge 70 strips are then secured in position by driving nails 10, therethrough from the sides of the support.

The ends of the bristles may be first 75 dipped in cement, or the cement may be applied directly to the sides of the slot in the brush and to the wedge member. The tuft of bristles is then inserted into the slot either manually or by machines, and the wedge strip then driven into place.

While the wedge pieces 9, grip the ends 80 of the bristles firmly, it is desirable to also employ cement to hold the individual bristles together and also to attach the bristles to the support 4, and the wedge 85 strips 9. I have found that a very suitable cement for this purpose may be made by mixing equal parts of shellac, white lead and rosin. This cement is insoluble in water and is unaffected by moderate heat so that the 90 bristles are firmly held in place at all times.

It will, of course, be evident that although two slots are shown for the insertion of bristles therein, only one may be used or if desired, a larger number than two. Also it 95 is not essential that the wedge member be inserted down the middle of the rows of bristles as shown in the drawings as it may be inserted along one side so as to force all the bristles against the opposite wall of the 100 slot.

After the bristles have been secured to the support 4, the projecting ends of the bristles are trimmed flush with the upper surface of the support and a layer of glue or other 105 adhesive applied thereto and the top piece 5, laid thereon, and further secured to the support by means of the screws 6.

Where the brush is to be used in a house, it is desirable to pad the corners of the brush 110

so that they will not injure the walls or furniture. This may conveniently be accomplished by employing a strip of rubber 11, which is passed around the ends of the brush 5 head and secured thereto by nails or screws 12, or suitable cement.

I am aware that numerous details of construction may be varied through a wide range without departing from the principles 10 of this invention and I therefore do not propose limiting the patent granted otherwise than necessitated by the annexed claim.

I claim as my invention:

A brush, comprising a head, having a 15 holder and a back piece, said holder having slots therein extending therethrough from front to back and extending lengthwise thereof less than the whole length of said backpiece, whereby each end of each slot is 20 closed by an end portion of the back piece,

bristles completely and uniformly filling each slot from end to end thereof, a wedge-shaped strip in each slot, the edge of the wedge being toward the front of the brush, the back of the wedge and the back ends 25 of the bristles being flush with the rear face of the holder, the back piece contacting with said rear face of the holder, the rear ends of the bristles and the backs of the wedges, waterproof cement securing the bristles, 30 wedges and back piece together, and supplemental fastening means securing the wedges in the slots and the back piece to the holder.

In testimony whereof I have hereunto subscribed my name in the presence of two 35 subscribing witnesses.

WILLIAM FEDER.
